UNITED STATES PATENT OFFICE.

MORRIS SCHWERIN, OF NEWARK, NEW JERSEY.

IMPROVEMENT IN FASTENINGS FOR BAGS.

Specification forming part of Letters Patent No. **147,866**, dated February 24, 1874; application filed December 17, 1873.

To all whom it may concern:

Be it known that I, MORRIS SCHWERIN, of Newark, in the county of Essex and State of New Jersey, have invented certain new and useful Improvements in Fastenings for Bags; and I do hereby declare the following to be a full, clear, and exact description of the invention, such as will enable others skilled in the art to which it pertains to make and use it, reference being had to the accompanying drawings, which form part of this specification.

The nature of my invention relates to an improvement in fastenings for traveling-bags; and it consists in the arrangement and combination of parts, which will be more fully described hereafter, whereby the fastening is cheapened in construction and rendered more efficient in operation than as heretofore used.

The accompanying drawings represent my invention.

a represents an ordinary traveling-bag, having a pocket on one side, which is covered by the flap *c*. Secured to this flap, in the usual manner, are the two straps *d*, which are provided with elastics or rubbers, so as to be extensible in fastening and unfastening. Attached to the outer side of the pocket, by rivets, or in any other suitable manner, are the plates *e*, which have a part of their upper ends cut away, so as to form the tongue or

projection *g*, which is then bent downward so as to form the hook *i*. To the under or inner side of each strap *d* is riveted a U-shaped catch, *o*, the rivets of which pass outward through both straps and metal plate *n* on the outside.

This fastening is very cheap and simple, and the straps are not weakened by having holes punched through them, as has heretofore been the case.

If so desired, the hook and catch may be reversed, the hook being fastened to the strap, and the catch to the pocket.

By the addition of the plates *n* the straps are strengthened, and the rivets prevented from tearing out.

Having thus described my invention, I claim—

As a fastening for bags and other articles, the combination of the strap *d*, hook *i*, catch *o*, and plate *n*, substantially as shown and described.

In testimony that I claim the foregoing I have hereunto set my hand this 13th day of December, 1873.

MORRIS SCHWERIN.
